UNITED STATES PATENT OFFICE.

FRITZ ERICKSON, OF PHILIPSBURG, MONTANA.

STOCK-WATERING APPARATUS.

1,322,682.

Specification of Letters Patent. Patented Nov. 25, 1919.

Application filed July 23, 1917. Serial No. 182,256.

To all whom it may concern:

Be it known that I, FRITZ ERICKSON, a citizen of the United States, residing at Philipsburg, in the county of Granite and State of Montana, have invented certain new and useful Improvements in Stock-Watering Apparatus, of which the following is a specification.

This invention relates to improvements in stock-watering apparatus and its object is to provide means for supplying a series of drinking-troughs from a common source. A further object is to provide means whereby any trough in the series may be inverted to permit it to be thoroughly cleansed and drained of sediment when necessary. With the foregoing and other objects in view the invention consists in the combination and arrangement of parts to be hereinafter fully described, pointed out in the claims and illustrated in the accompanying drawing which forms a part of this specification and in which—

Figure 1 is a view of my apparatus in elevation.

Fig. 2 is an enlarged front elevation of a single trough.

Fig. 3 is an end view of a trough showing the supporting element for the apparatus.

Fig. 4 is an enlarged fragmentary sectional view illustrating the water-tight type of joint employed.

Fig. 5 is an end elevation of a single trough in inverted position.

Like reference characters denote corresponding parts throughout the several views.

I provide a reservoir 1 supplied by the feed pipe 2 and provided with the faucet 3. In metal supports or bearings 4 pipe-links 5 are supported, the several links being connected by the water-tight couplings 6 each of which comprises a pair of threaded cups as shown in Fig. 4. Metal supports 7 secured to a wall or supporting surface 8 also contribute to the support of the pipe-links 5 and said supports 7 serve as anchors for the forks or catches 9, 10 carried by adjacent faces of each trough 11, said troughs receiving water from the pipe-links 5 and being pivotally arranged upon said links.

The forks 9, 10 are made of spring metal and serve, respectively, in connection with the supports 7 to retain the troughs individually in normal position or in inverted position. As the water from the faucet 3 fills the trough 11 therebeneath it flows through the pipe-links 5 to the next trough and so on through the series of troughs and out through the vent pipe 12 into the waste trough 13. The arrangement provides for fresh running water at all times for the stock.

To drain and clean any of the troughs the water is turned off at the faucet and the trough inverted, as shown in Fig. 5, and in this position it may be readily cleansed and scrubbed by hand if desired.

What is claimed is:—

1. In stock watering apparatus comprising a reservoir provided with a faucet, a plurality of spaced bearings, pipe links having their ends disposed in said bearings, water-tight couplings connecting said pipe links within said bearings, water troughs pivotally carried by said pipe links, auxiliary supports for said pipe links, and resilient members arranged upon adjacent faces of each water trough for alternate engagement with said auxiliary supports whereby said water trough is retained alternately in normal or inverted position.

2. In stock watering apparatus comprising a reservoir provided with a faucet, a plurality of spaced bearings, pipe links having their ends disposed in said bearings, water-tight couplings connecting said pipe links within said bearings, water troughs pivotally carried by said pipe links, auxiliary supports for said pipe links, and spring-forks carried by said water troughs for engagement with said auxiliary supports.

In testimony that I claim the foregoing as my own I have hereto affixed my signature in the presence of two subscribing witnesses.

FRITZ ERICKSON.
